United States Patent Office

Des. 219,114
Patented Nov. 3, 1970

219,114

BURST TESTER, OR SIMILAR ARTICLE

Fred Schlegel, Wheeling, Ill., assignor to E. J. Cady
Company, Chicago, Ill., a corporation of Illinois

Filed Sept. 2, 1969, Ser. No. 18,960

Term of patent 14 years

Int. Cl. D10—08, 99
U.S. Cl. D52—6

FIG. 1 is a perspective view of a burst tester, embodying my new design, showing the front and one side thereof. FIG. 2 is a perspective view of the burst tester of FIG. 1 showing the opposite side and front thereof.

The undisclosed rear portions of the article are planar and unornamented.

I claim:

The ornamental design for a burst tester, or similar article, substantially as shown and described.
